UNITED STATES PATENT OFFICE.

AXEL M. NELSON, OF CHICAGO, ILLINOIS, ASSIGNOR TO GENERAL AMERICAN TANK CAR CORPORATION, OF CHICAGO, ILLINOIS, A CORPORATION OF WEST VIRGINIA.

TANK CAR.

Application filed July 23, 1921. Serial No. 487,091.

To all whom it may concern:

Be it known that I, AXEL M. NELSON, a citizen of the United States, residing at Chicago, in the county of Cook and State 5 of Illinois, have invented a new and useful Improvement in Tank Cars, of which the following is a specification.

My improvement relates more particularly to the tank portion of a tank car, and 10 more especially to the means for supporting within the tank the coils of pipe through the medium of which the contents of the tank are heated.

My primary objects are to provide improvements in such supporting means, to the end that the assembling and uniting of the pipes on initial installation thereof may be facilitated, repairs to the pipes or to the tank below the pipes may be readily made, 20 and the cleaning of the tank facilitated, and other objects as will be manifest from the following description.

Referring to the accompanying drawings:

Figure 1 is a view in side elevation, with 25 certain parts broken away and others in section, of a car tank constructed in accordance with my invention. Figure 2 is a plan view of the heating pipes and the supporting brackets therefor. Figure 3 is a section 30 taken at the line 3—3 on Fig. 1 and viewed in the direction of the arrow; and Figure 4, a view in end elevation of the right hand end of the tank in Fig. 1.

The car tank shown is represented at 5, 35 this tank being of well known construction and comprising a cylindrical body portion 6 surmounted by the usual dome 6^a, and the end plates 7 and 8 which telescope at their annular flanged portions 9 and 10 with the 40 ends of the body portion 6 to which they are secured in any desirable manner.

The heating coils are shown as provided in two units, one at each side of the bottom longitudinal center line of the tank, each of 45 these units being in the form of a coil represented at 11 and formed of a series of parallel pipes 12 and return bends 13 connected with the opposite ends of the pipes 12, the ends of these coils being represented at 14, 50 15, 16 and 17. The coil units, which extend lengthwise of the tank, are transversely curved as represented in Fig. 3 to extend substantially concentric with the wall of the body portion 6 of the tank, and are sup-

ported, preferably in spaced relation, to the 55 side wall of the tank, on a bracket structure which is formed of two sections 18 and 19 which are transversely curved to correspond with the curvature of the coil sections 11, these bracket sections being hingedly 60 supported at their lower ends preferably coincident with the bottom longitudinal center line of the tank to permit them to be independently swung upwardly, together with the pipe coils supported thereon, as for example to the positions represented in dotted lines in Fig. 3.

Each of the bracket sections 18 and 19 70 comprises a series of bars 20 which preferably extend in parallel relation and are provided of any suitable number, four for each section being shown, these bars being secured at their upper ends by bolts 21^a to cradle end brackets 21 affording flanges 22 which rest against the inner surface of the body 6 75 of the tank and to which they may be connected as by the rivets 23. The bars 20 intermediate their ends are provided with cradle brackets 24 of general yoke-shape as shown, these brackets being secured to the bars 20 80 as by means of the bolts 25 and at their outwardly-directed ends 24^a to the body 6 of the tank, as by the rivets 26. The lower ends of the bars 20 are reduced as represented at 27 to cause them to overlap as 85 shown, at which portions they extend between angle uprights 28 secured, in pairs, as by means of the rivets 29, to the body 6 of the tank along its longitudinal center line, these pairs of uprights forming supports 90 for hinge pins 30 extending therethrough and through the overlapping end portions 27 of opposed bars 20. The various pipes forming the coil units 11 rest upon the bracket sections 18 and 19 and are secured 95 thereto as through the bottom of the U-bolts represented at 31 which partially embrace the various pipes and extend at their ends through openings in the bars 20, the ends of these U-bolts being threaded and having 100 screwed thereon the nuts 32 for holding the pipes in position on the bracket arms 20. The pipes 14, 15, 16 and 17 extend through the end wall 7 of the tank, fluid-tight joints 105 therebetween being provided for in any suitable manner, as for example as common in constructions of this character. The portions 14 and 17, which are shown as con-

nected together by the pipe 33, may serve as the inlet for the heating medium, and the pipes 15 and 16 as the outlets therefor.

Further securing means for the pipe coils 5 are represented at 34, these means being in the form of brackets secured to the inner surface of the body 6 of the tank and provided with U-bolts 35 which partially surround the adjacent return bends 13 of the 10 pipe coils, these means serving primarily as anchorages to prevent the coils from shifting lengthwise of the tank.

In the assembly of the various parts of the structure referred to, the pipe sections 15 12 and 13 introduced into the tank in disassembled relation, are assembled to the position shown in Fig. 2 and in this condition are connected together, preferably by welding them, at the joints therebetween represented at 36.

It will be noted that the pipe coil sections thus provided at each side of the center line of the car, together with the bracket arm members 20 form radiator structures at opposite sides of the car each with a hinge connection to the car at substantially the bottom center line thereof, and that when the bolts 21^a and 25 connecting the cradle members 21 and 24 with the arm members 20, and 25 the U-bolts 35, are removed, these radiator structures may be swung upwardly on their hinges independently of each other to the dotted line positions in Fig. 3, thereby greatly facilitating the making of repairs to 30 these pipes, and the shell of the tank below the pipes and greatly facilitating the cleaning of the tank.

In the particular construction illustrated it is contemplated that the pipes 14, 15, 16

and 17 be cut through at the interior of 40 the tank, in order to permit of these radiator structures being swung upon the hinged connections as stated, these severed portions of the pipes being again connected together 45 as by welding them together after the radiator structures have been swung back to their normal position. It will be understood, however, that if desired couplings may be provided for the outlet and inlet portions of the pipes, to avoid cutting and 50 reuniting of these pipes for the purpose stated.

While I have illustrated and described a particular construction embodying my invention, I do not wish to be understood as 55 intending to limit it thereto as the same may be variously modified and altered without departing from the spirit of my invention.

What I claim as new, and desire to secure by Letters Patent, is:

1. A cylindrical tank containing a bracket structure formed of a plurality of curved bars extending adjacent the curved side wall of the tank and hingedly connected with the tank, and a radiator coil carried by said 65 bars.

2. A cylindrical tank containing bracket structures located at opposite sides of the center line of the tank and each comprising a plurality of curved arms spaced apart and 70 extending adjacent the curved sides of the tank, means hingedly connecting said bars at their lower ends to said tank, and separate radiator coils extending lengthwise of the tank and crosswise of said bars and carried by the latter.

AXEL M. NELSON.
